UNITED STATES PATENT OFFICE

2,333,483

LIVING EQUIPMENT OR FURNITURE

Paul Marzillier, Milwaukee, Wis.

Application January 21, 1941, Serial No. 375,181

5 Claims. (Cl. 5—2)

The invention relates to a portable unitary piece of living equipment or furniture which can be readily put into its appointed location, which fits into many types of rooms and buildings and which is designed to be readily converted so as to serve a plurality of uses.

The principal object of the invention is to provide a unitary article of living equipment which is arranged to normally conceal an extensible bed, while at the same time a simple manipulation converts the device for another use such as a writing desk and/or bookcase, while in both positions affording access to storage cabinets which themselves may be adapted to a plurality of uses.

Another object of the invention is to provide a piece of living equipment of aforementioned type which in either its closed or open position does not detract from the appearance of the room in which it is placed, but on the contrary lends proprietary atmosphere to such room and gives it the appearance and usefulness of a conventional bed or living or drawing room or the like.

Another object is to provide for a novel method of combining a bed with other features incorporated in a single piece of equipment.

Another object is to provide a piece of room equipment which does not require that the room be specially designed for its placement.

Another object is to provide a piece of convertible living equipment which when arranged for either use preserves the atmosphere of the room typical of such use.

The accompanying drawings illustrate one embodiment of the invention in which the device normally serves as a combination desk and bookcase, while in the extended position the device serves as a bed. At the same time the device provides storage spaces for books, files, wardrobe and the like. In the accompanying drawings

Fig. 1 shows the device in the closed position installed in a room.

Fig. 2 shows the desk portion opened for use as a writing desk or the like.

Fig. 3 shows the device completely opened with the bed in the position for use.

Fig. 4 shows the device when used as a desk with one of the compartments opened to permit access to the storage space in the desk, while

Fig. 5 is a cross section through the device in the position shown in Fig. 2.

Referring to the drawings the same illustrates a cabinet having a bottom wall 1, a rear wall 2, end walls 8 and a top 3, hinged at 4 to the rear wall 2, so that it may be opened to afford access to a compartment 5. The compartment 5 is

formed by a bottom member 6, a front wall 7, the top part of rear wall 2, the top 3 and the end walls 8. The latter also forms with the bottom wall 1, the rear wall 2 and the wall 6 a lower compartment 9 adapted to receive the frame 10 of a bed. The frame 10 comprises the partition member 11, side walls 12 and front and rear rails 13 which are arranged to receive a bed spring 13a and mattress 14 of any desired conventional type, suitable fastening means being provided to hold the spring and mattress in the frame when the same is tilted to a vertical position.

The frame 10 is provided with front legs 15 and its rear end is hinged by a pivot 17 extending through a side wall attached to a forward extension 18 of the bottom 1 and side members 20 of the frame 10. The front legs 15 are preferably pivoted so that in the vertical position of the bed frame they fold inwardly so as not to interfere with the cabinets 23. Fastened to the front or bottom side of the frame 10 intermediate of its ends is a longitudinal wall or shelf 19 which together with side members 20 attached to frame 10 and a top member 21, attached to the main frame, form a rectangular opening or compartment which may be closed by a lid 22 which is hinged to permit opening thereof to form an extension of the bottom 19 so as to serve as a writing surface, and the compartment may be provided with any desired arrangement of pigeon holes or compartment for the storage of writing material and the like. Hinged to the side walls 8 on either side of the device are cabinets 23 which may have any internal arrangement of shelves or the like and which as shown in Fig. 3 may be swung into any desired angular position and thus are made accessible and in this position permit the lowering of the bed to its normal position. Front and rear may be closed by doors. The cabinets 23 may be subdivided in any desired manner and may be provided with doors on either side as may be convenient to provide access to the interior with the equipment in the position shown in Figs. 1, 2 and 3 respectively. The shelf 19 together with the bottom extension 18 and the side member 20 form in the closed position a lower well 24 to provide for leg space for a user of the desk, when the leaf 22 is in the horizontal position. This lower well 24 may be provided with a tiltable box 25 adapted for the reception of pillows or any other material desired. Said box 25 may be suitably hinged at 26 on the side member 20 to be swung in and out as desired and may be so arranged as to afford additional leg space for a user of the desk platform or lid 22 and to brace the latter in the open

position, and may be latched in the closed position by any suitable means.

In order to protect the contents of the desk compartment when the bed is swung downward it is desirable to provide a further partition 29 at right angle and attached to the bottom member 11 to move therewith. In the closed position the lid 22 abuts the partition 29. The latter is preferably made transparent or provided with a transparent insert to permit light from a lamp 30 to shine on the writing surface. The lamp 30 may be a tubular fluorescent lamp attached to the under side of the extension 21.

In the device shown in the drawings the compartments 23 do not extend down to the bottom extension 18 but interposed between the former and the latter is a compartment 27 which is provided with a drawer 28 for additional storage. The compartments 27 are of a height to permit the bed upon being opened to clear these compartments or drawers.

To close the device the bed is first folded upward, thereafter the compartments 23 are swung inwardly into the position shown in Fig. 1 to present the appearance of a closed desk. If it is desired to use the desk it is only necessary to open the lid or shelf 22 as shown in Fig. 2, and/or to swing out the cabinets 23.

Fig. 4 shows the inside of one of the cabinets 23 which may be arranged to serve as wardrobes or the like alone, or as aforesaid may serve as a wardrobe accessible when swung outwardly as in Figs. 3 and 4 while the front part which may be closed by a door and which is accessible when the cabinets are swung inwardly as in Figs. 1 and 2, may serve as a book cabinet or the like.

What I claim as new and desire to secure by Letters Patent is:

1. A multiple utility unitary cabinet of the character described, comprising, a main housing forming a compartment open at its front and having its top and bottom walls extending frontwise beyond its side walls, a bed frame provided with a partition arranged to receive a bed on one side thereof and pivoted to said housing adjacent to the front edge of said bottom wall for rotation about a horizontal axis, said partition being substantially in line with the front edge of said side walls when said frame is in a vertical position to form with said housing a closed space for storing a bed, said frame in the horizontal position being substantially entirely outside of the perimeter of said housing, said partition being provided at its other side and intermediate of its vertical ends with a secondary compartment arranged to be accessible for use with said frame in the vertical position, and a pair of storage cabinets, one each hinged to the front edge of one of said side walls for rotation about a vertical axis, and rotatable to a position when said frame is in a vertical position within the perimeter of said housing to partially cover said partition, said cabinets being further arranged to be swung outside of the perimeter of said housing to partially cover said partition, said cabinets being further arranged to be swung outside of the perimeter of said housing to permit rotation of said frame to the horizontal position.

2. A multiple utility unitary cabinet of the character described, comprising, a main housing forming a compartment open at its front and having its top and bottom walls extending frontwise beyond its side walls, a bed, a bed frame provided with a partition having said bed mounted on one side thereof and pivoted to said housing

adjacent to the front edge of said bottom wall for rotation about a horizontal axis, which is parallel to the longitudinal axis of said bed, said partition being substantially in line with the front edge of said side walls when said frame is rotated to a vertical position to form with said housing a closed space for storing said bed, said frame in the horizontal position being substantially entirely outside of the perimeter of said housing, said partition being provided at its other side intermediate of its vertical ends with a secondary compartment arranged to be accessible for use with said frame in the vertical position, and a pair of storage cabinets, one each hinged to the front edge of one of said side walls for rotation about a vertical axis, and rotatable when said frame is in a vertical position to a position within the perimeter of said housing to partially cover said partition and abut the vertical sides of said secondary compartment, said cabinets being further arranged to be swung outside of the perimeter of said housing to permit rotation of said frame to the horizontal position.

3. A multiple utility unitary cabinet of the character described, comprising, a main housing forming a compartment open at its front and having its top and bottom walls extending frontwise beyond its side walls, a bed frame provided with a partition adapted to have a bed mounted on one side thereof and pivoted to said housing adjacent to the front edge of said bottom wall for rotation about a horizontal axis, which is parallel to the longitudinal axis of said frame, said partition being substantially in line with the front edge of said side walls when said frame is rotated to a vertical position to form with said housing a closed space for storing a bed, said frame in the horizontal position being substantially entirely outside of the perimeter of said housing, said partition being provided at its other side and intermediate of its vertical ends with a secondary compartment arranged to be accessible for use with said frame in the vertical position, said secondary compartment having a pivoted front for closing the same, and a pair of storage cabinets, one each hinged to the front edge of one of said side walls for rotation about a vertical axis, and rotatable when said frame is in a vertical position to a position within the perimeter of said housing and into the respective corner formed by said partition and one of the vertical sides of said secondary compartment, said cabinets being further arranged to be swung outside of the perimeter of said housing to permit rotation of said frame to the horizontal position.

4. A multiple utility unitary cabinet of the character described, comprising, a main housing forming a compartment open at its front and having its top and bottom walls extending frontwise beyond its side walls, a bed, a bed frame provided with a partition having said bed mounted on one side thereof and pivoted to said housing adjacent to the front edge of said bottom wall for rotation about a horizontal axis, which is parallel to the longitudinal axis of said bed, said partition being substantially in line with the front edge of said side walls when said frame is rotated to a vertical position to form with said housing a closed space for storing said bed, said frame in the horizontal position being substantially entirely outside of the perimeter of said housing, said partition being provided at its other side intermediate of its vertical ends with a secondary compartment arranged to be accessible for use with said frame in the vertical position,

said secondary compartment having a pivoted front for closing the same, and a pair of storage cabinets, one each hinged to the front edge of one of said side walls for rotation about a vertical axis, and rotatable when said frame is in a vertical position to a position within the perimeter of said housing and into the respective corner formed by said partition and one of the vertical sides of said secondary compartment, said cabinets being further arranged to be swung outside of the perimeter of said housing to permit rotation of said frame to the horizontal position.

5. A multiple utility unitary cabinet of the character described, comprising, a main housing forming a compartment open at its front and having its top and bottom walls extending front-wise beyond its side walls, a bed, a bed frame provided with a partition having said bed mounted on one side thereof and pivoted to said housing adjacent to the front edge of said bottom wall for rotation about a horizontal axis, which is parallel to the longitudinal axis of said bed, said partition being substantially in line with the front edge of said side walls when said frame is

rotated to a vertical position to form with said housing a closed space for storing said bed, said frame in the horizontal position being substantially entirely outside of the perimeter of said housing, said partition being provided at its other side and intermediate of its vertical ends with a secondary compartment arranged to be accessible for use with said frame in the vertical position, and provided with an intermediate partition to divide it into an upper and a lower section, a lid pivotally attached to said partition to afford a horizontal working surface and alternately to close said upper section, and a pair of storage cabinets, one each hinged to the front edge of one of said side walls for rotation about a vertical axis, and rotatable when said frame is in a vertical position to a position within the perimeter of said housing and into the respective corner formed by said frame partition and one of the vertical sides of said secondary compartment, said cabinets being further arranged to be swung outside of the perimeter of said housing to permit rotation of said frame to the horizontal position.

PAUL MARZILLIER.

CER

A CORRECTION.

Patent No. 2,333,483.

November 2, 1943.

PAUL MARZILLIER.

It is hereby certified that error appears in the printed specification of the above numbered patent requiring correction as follows: Page 2, first column, lines 64 to 66 inclusive, claim 1, strike out "to partially cover said partition, said cabinets being further arranged to be swung outside of the perimeter of said housing"; and that the said Letters Patent should be read with this correction therein that the same may conform to the record of the case in the Patent Office.

Signed and sealed this 25th day of January, A. D, 1944.
